UNITED STATES PATENT OFFICE.

GEORGE NISSENSON, OF NEW YORK, N. Y.

ELEVATOR SAFETY DEVICE.

1,262,831.

Specification of Letters Patent. Patented Apr. 16, 1918.

Application filed October 8, 1915. Serial No. 54,768.

To all whom it may concern:

Be it known that I, GEORGE NISSENSON, a citizen of the United States, and a resident of the city of New York, borough of Manhattan, in the county and State of New York, have invented a new and Improved Elevator Safety Device, of which the following is a specification.

My invention relates to safety devices for elevators, lifts and similarly operating apparatus, and to means of controlling and starting a water, steam or otherwise operated elevator machine, which control is dependent upon and correlated to the position of the elevator car, platform and the like, and of the door or doors of the elevator shaft, the object of the present invention being to provide an automatic device, whereby, when a door of the elevator-shaft is opened to permit access to or egress from an elevator car, platform or the like, the operating sheave or part of the elevator will be clutched or locked, and will remain so clutched or locked during the entire time that the door so remains open and will prevent the starting of said elevator car, platform or the like, until the said door is closed and locked.

The invention consists of novel parts, and combinations of the same, as hereinafter more fully described, and as pointed out in the claims.

A practical embodiment of the invention is represented in the accompanying drawings, forming a part of this specification, in which similar characters of reference indicate corresponding parts in all the views.

Figure 1 is a front view of the device, as arranged for attachment in the operation of a hydraulic elevator, showing the toothed plate engaged with the toothed rack, attached to the rim of an operating sheave, commonly in use to control the admission and release of water pressure to and from the cylinder of an elevator machine.

Fig. 2 is a similar view showing the toothed or grooved plate, disengaged from the toothed or grooved rack of the rim of such an operating sheave.

Fig. 3 represents the door switch attached to the door frame of an elevator-shaft door, with the electric contact shown to be separated upon the door being closed.

Fig. 4 represents the door switch, at-

tached to the door frame of an elevator-shaft door, showing door partly open and switch contacts engaged.

The device consists of a standard electric lifting solenoid, 1, mounted and made fast to an iron frame 2, by bolts 2^a and 2^b. The solenoid 1 is connected by means of a complete wire circuit with a door switch 40. Within the core of the solenoid 1 is a movable member 3, which has a slight inward movement as soon as an electric circuit is established through the said complete wire circuit. The solenoid 1, its movable member 3, and the frame 2, which form a power unit, are joined to and made permanent with the member of an iron bracket 4, by means of bolt 5, and bracket 23. The frame is strengthened by a brace 6, fastened together with the bolts 6^a and 6^b. Within this frame 4, 4 and 6 is mounted the mechanical movement of the device, which consists of a movable rod 7, one end of which extends through frame member 4 and is provided with a screw thread 11 to receive the movable member 3, the latter having in its center a corresponding threaded aperture 80 to allow the threaded end 11 of the rod 7 to be introduced or withdrawn so as to permit of its adjustment to the required length, after which adjustment it is locked with the lock nut 12. The other end of said movable rod 7 extends through a bracket 8 to receive a spiral spring 9 and nut 10 to retain the spring. A collar 20, fitted on rod 7 and set screw 21 are also provided for adjustment of the distance of travel of movable member 3 and rod 7, a shifting of the stop collar 20 toward the bracket 8, shortening the distance of travel of rod 7 and member 3. An aperture 22 is provided in movable rod 7 to engage one end of a lever 24, pivoted at its median distance on the bracket 23. The other end of lever 24 is connected with lever 29 by means of a link 25, pivoted at 26^a and 26^b. Link 25 is introduced into and moves freely within a slotted aperture 34, provided in the brace 6 of frame 4, 4, the said free movement of the link 25 within said slotted aperture being produced whenever lever 24 is moved to or from either of its extreme positions by the motion of rod 7. The apertures 30^a in the lever 24 are for the purpose of adjustment and of shortening or lengthening the distance of travel of link

25 and of lever 29 by introducing the pivot 26^a into one of the apertures 30^a. One end of the lever 29 is pivoted upon brace 6 at 27, and the opposite end is free. The lever 29 has a radial movement upon its fixed or pivoted end 27, which movement is actuated by the movement of lever 24 and link 25. The free end of lever 24 is provided with a toothed or grooved block 28, fastened to 10 lever 29 by bolts 31^a, 31^a. Said block 28 is set to engage a corresponding toothed or grooved rack 32, which is attached to an operating sheave 33 or the like, by bolts 35 or other suitable means. The electric solenoid 1, and its movable member 3, are operated and controlled by means of a switch 40, which comprises an outer frame or casing 48 and a push rod 41, partly protruding through an aperture in one side of said 15 frame or casing 48 and moving in and through said aperture. Push rod 41 has at its inner end an insulating plate 42, the ends of which are carried and move upon two stationary guide rods 49, 49, through 20 an aperture at each end of plate 42, provided for that purpose, said rods 49, 49 being fixed to opposite sides. Attached to and carried by push rod 41 and insulating plate 42 is a knife blade 43. The push rod 41 is 25 normally held in forward position by means of springs 44, 44, carried on the guide rods 49, 49, and bearing at one end against insulating plate 42. The second and stationary insulating plate is fixed within the 30 frame or casing 48 upon the side through which push rod 41 protrudes and is provided with an aperture in line with that on the same side of the frame or casing 48, so as to permit push rod 41 to move in line 35 through plate 45 and the side of frame 48. The insulating plate 45 carries electric connections 46, 46, which are arranged for engagement by knife blade 43. Knife blade 43 engages the electric connections 46, 46 40 when push rod 41 and plate 42 are in forward position, thereby completing the electric circuit to the solenoid, and only becoming disengaged and breaking said circuit when push rod 41 and plate 42 are 45 depressed by pressure against the outer end of push rod 41. By 47 is represented conventionally a door of an elevator shaft, which in Fig. 4 is shown open and without its pressure exerted upon push rod 41, 50 which through the action of the springs 44, 44 bearing upon plate 42 is in its forward position when the knife blade 43 is in contact with the electric connections 46, 46; and in Fig. 3 is shown closed, with its pressure 55 exerted upon push rod 41, which, with plate 42 and knife blade 43, are thereby depressed, the knife blade 43 being then out of contact with the electric connections 46, 46. Although the form of switch described 60 65 is preferred for use in connection with the

device, it may be replaced by any other form of switch or other contact making and breaking means.

From the above description it will be evident that as soon as a complete circuit is established between the door switch and the lifting solenoid, as in the case when the door of an elevator-shaft is left open (Fig. 3), the electric current energizing the solenoid will draw its movable member 3 and rod 7 70 and thereby draw or move lever 24 at its lower end toward the left so as to swing upon its pivoted point on bracket 23, and the movement of lever 24 will be imparted to lever 29 by means of the link 25, the said movement bringing the position of the link 25 directly in line with the position of lever 24 at 26^a. The movement of lever 29 will cause the toothed or grooved block 28 to engage the toothed or grooved rack 32, attached to the operating sheave 33, and thereby will prevent the rack and the operating sheave from turning and will keep it in a stationary position. When block 28 and rack 32 are thus engaged, lever 24 and link 25 being placed in a straight line with reference to each other and rigid, will prevent the pressure of the operating sheave 33 on block 28 from breaking the line of rigidity of lever 24 and link 25. Lever 29 and rack 90 95 99 100 105 110 115 120 125 130 32 will remain thus engaged or clutched until the electric circuit is broken by the door switch contacts being separated when the door is closed (as in Fig. 3), when the action of the spring 9 will pull the movable rod 7 back to its former position, and the motion being imparted to lever 24 and link 25 will bring them back to their respective former positions, and the lever 29 connected with them will consequently disengage the toothed or grooved block 28 from the toothed or grooved rack 32, which is attached to the rim of the operating sheave 33 or the like, thereby permitting the free movement of the latter in any direction and placing the elevator machine again in motion.

When the elevator has been stopped at a given floor, it will be understood that some part of the toothed rack 32 stands opposite to some part of the toothed bar 28. As is well known, there is considerable leeway in finding the neutral position of the operating sheave. The present device is so constructed that, no matter how slightly the toothed rack and bar may overlap, an effective locking action will be secured when the door is opened, holding the controller in neutral position, thus operating the electrical connections from the door switch or detector 40, which thrusts the toothed bar toward the controlling sheave. The toggle 24, 25 not only thrusts the toothed bar toward the sheave, but when the teeth are engaged it locks them positively against an accidental 130

displacement. This effective locking is obtained no matter at what part of its neutral position the sheave may stand, so long as one or more teeth of the bar overlap one or 5 more teeth of the rack. In consequence of this no longitudinal adjustment of the bar or rack is needed, since they will operate in any given position, and when locked there is no possibility of accidental readjustment 10 of the controlling sheave.

Although this device is shown as applied to the operating sheave of an elevator machine, it may be used in application to any other machine or apparatus where the automatic control or operation of a radially moving part is desired by the make and break 15 of an electric circuit, produced by the use of a switch attached to a door, gate or the like, or other circuit making and breaking 20 means, and although this device is shown to be operated by electric power acting through the door switch upon the lifting solenoid of the device, this power may be substituted or replaced by air, oil or water pressure, in 25 which case the solenoid is to be substituted or replaced by a cylinder and piston, or other similar equivalent mechanical means.

I claim as my invention:

1. An elevator safety device, including in 30 combination, a rotatable controller for controlling the power apparatus, a detector

operated by the closed or unclosed condition of an elevator door, a peripherally operating locking means adapted to positively engage and lock the controller in any position within the range of its neutral movement, and connections from said detector for operating said locking means when the door is not properly closed, said locking means comprising a pair of toothed racks, 35 one on the controller periphery, and said connections comprising a toggle for forcing the other rack into engagement with the first.

2. An elevator safety device, including in combination, a rotatable controller for controlling the power apparatus, a detector operated by the closed or unclosed condition of an elevator door, a peripherally operating locking means adapted to positively engage and lock the controller in any position within the range of its neutral movement, and connections from said detector for operating 40 said locking means when the door is not properly closed, said locking means comprising a pair of toothed racks, one on the controller periphery, and said connections comprising a toggle for forcing the other rack into engagement with the first. 45
